UNITED STATES PATENT OFFICE.

SAMUEL H. CONWELL, OF CHICAGO, ILLINOIS, ASSIGNOR TO WALTER P. MURPHY,
OF NEW YORK, N. Y.

GONDOLA-CAR END WALL.

Application filed February 6, 1920. Serial No. 356,693.

To all whom it may concern:

Be it known that I, SAMUEL H. CONWELL, a citizen of the United States, residing at Chicago, in the county of Cook and State 5 of Illinois, have invented certain new and useful Improvements in Gondola-Car End Walls, of which the following is a specification.

My invention relates to the construction 10 of railway cars, more particularly gondola cars, and has for a primary object to provide a reinforced sheet metal panel for the end wall of a railway car of this type together with novel means for rigidifying 15 the marginal portions of the panel and to provide means for securely attaching the panel to the side wall structure and under-framing of the car whereby the end wall of the car will be rigidified to effectively resist 20 the various thrusts and pressures to which car end structures are subjected.

A further and more specific object of the invention is to provide a novel top chord construction for a sheet metal gondola car 25 which will be very strong and rigid so as to be capable of withstanding the rough usage to which this part of the car is subjected, and which, moreover, will give reinforcement to the entire superstructure of the car.

The invention consists in the new and improved constructions, arrangements and combinations of parts and devices relating 30 to railway car constructions, as will be hereinafter described and claimed, for carrying out the above stated objects and such other incidental objects as will appear from the following description of my invention.

My invention is illustrated in certain preferred embodiments in the accompanying drawings, wherein:

Fig. 1 is a vertical section through one end of a railway car of the gondola type, illustrating an end construction made in accordance with my invention.

Fig. 2 is a plan view illustrating the manner in which the end structure is secured to the side wall structure of the car.

Fig. 3 is a sectional plan taken on line 50 3-3 of Fig. 1.

Fig. 4 is a fragmentary view in elevation showing the upper corner of the car.

Fig. 5 is a plan view illustrating a modified form of top chord construction.

Fig. 6 is a fragmentary view, in plan, 55 similar to Fig. 2 showing a further modified construction suitable for use in connection with cars having wooden corner posts.

Fig. 7 is a fragmentary vertical section 60 through the upper edge of a gondola car end wall showing a modified form of top chord for the said end wall panel.

Fig. 8 is a fragmentary view in section 65 through the upper portion of a gondola car end wall showing a further modified construction.

Fig. 9 is a similar view of another modification.

Like characters of reference designate 70 like parts.

Referring first to Figs. 1 to 4 inclusive of the drawings, I have shown and will describe my invention in connection with a gondola car construction though it will be 75 obvious that certain of the features embodied in this invention might be readily used in connection with box cars. I, therefore, do not wish to limit the invention to the specific use shown or to the structural 80 feature described except in so far as specific limitations may appear in the appended claims.

The end structure shown in Figs. 1 to 4 inclusive consists preferably of an end 85 panel made up of two sheets designated 10 and 11 respectively formed with a plurality of horizontally disposed corrugations 12-13 which extend uninterruptedly across the car from side to side thereof and terminate 90 with the usual tapered terminals 14, 15 within the edges of the sheets. The sheets are arranged face to face and secured together by rows of rivets 16 on opposite sides of the corrugations 12-13. The said 95 corrugations 12-13 are preferably disposed opposite one to another so as to provide hollow reinforcing beams which extend across the car end. The lower edges of the sheets are bent in opposite directions to 100

provide flanges 17-18 adapted to be secured to the underframing 19 of the car. The vertical edges of the sheets are bent rearwardly to provide angular attaching flanges 20-21 which overlap the outer and inner surfaces of the side walls 22 and are secured to said side walls by means of bolts 23. The upper edges of the sheet 10-11 are bent in opposite directions to provide a rigidifying chord for the upper margin of the end panel. This rigidifying chord consists preferably of webs 24-25 having depending reinforcing flanges 26-27 respectively. The top chord construction is firmly attached to the side wall structure of the car by means of angular stiffening members or gussets 28 riveted to the web 24 and web 25 of the chord member by rivets 29-30 respectively, overlapping the outer surface of the side walls and secured thereto by means of bolts 31 passing through the side wall boards 22 and bolts 32 passing through the side wall boards and also through the vertical attaching flanges 20-21 of the sheets 10-11 respectively.

In the modification illustrated in Fig. 5 the end panel consists of corrugated sheets 33-34 formed along their vertical edges with angular attaching flanges 35-36 respectively which overlap the side walls 37 of the car. The upper edge of the panel is rigidified by means of a top chord formed by turning the upper edge of the sheet 33 outwardly to provide a flange 38 and bending the upper edge of the sheet 34 inwardly to provide an oppositely disposed flange 39. When forming a metal sheet with rigidifying corrugations the edges of the sheet are distorted or drawn inwardly by the pressing operation. This fact is taken advantage of in the chord construction illustrated in Fig. 5 in that the upper edge of the sheet 34 is bent over without removing the irregular portion of the edge. By forming the flange 39 in this manner the flange is increased in width toward the sides of the car. The extremities of the flange 39 are preferably bent downwardly as indicated at 40 and are suitably secured to the vertical flanges 36 by bolts 41 passing through the side walls 37 of the car.

The modification illustrated in Fig. 6 shows an end panel in which the car structure is rigidified adjacent the corner posts 42 of the car. The vertical edges of the inner sheet of this structure are preferably bent as indicated at 43-44 so as to fit around the inner faces of the corner posts 42, the outer edge being bent rearwardly as indicated at 45 and secured to the side wall 46 of the car. The outer sheet designated 47 in this figure may be constructed substantially the same as the outer sheet in Figs. 1 to 4 inclusive and the end panel

may be secured to the side wall construction of the car by means of the gussets 28^a in substantially the same manner as that illustrated in Figs. 1 to 4 inclusive.

In Fig. 7, I have illustrated another modified form of end construction in which the top chord of the panel is provided by bending the upper edges of the sheets 48-49 in opposite directions as indicated at 50-51. A channel beam 52 is fitted over the flanges 50-51 and secured thereto by rivets 53.

In Fig. 8, I have shown a modification in which the end panel is composed of two sheets 54, 55, one flat and the other corrugated, having oppositely turned flanges 56, 57 forming the top chord of the end. The sheets are preferably secured together by rivets 58 on opposite sides of the corrugations 59 of the sheet 55. In Fig. 9 the arrangement is similar except that the top chord forming flanges are turned both in the same direction. Sheet 60, the outer sheet preferably is formed with corrugations and with an out turned flange 61 having a depending rim 62. The inner sheet 63 may be flat and is formed with an out turned flange 64 secured to flange 61 by rivets 65.

I claim:

1. In a railway car, the combination with the underframe and the side walls of the car, of a sheet metal end wall comprising metal sheets arranged face to face, formed with rigidifying corrugations arranged so that those of one sheet align with those of the other secured together at points between said corrugations, provided along their vertical edges with attaching flanges secured to the inner and outer surfaces of the side wall structures, and provided along their upper edges with substantially horizontal webs which together provide a rigidifying chord for said end structure.

2. In a railway car, the combination with the underframe and side walls of the car, of a sheet metal end wall comprising metal sheets arranged face to face, formed with horizontally extending rigidifying corrugations arranged so that those of one sheet align with those of the other secured together at points between said corrugations, provided along their vertical edges with attaching flanges secured to the inner and outer surfaces of the side wall structure, and provided along their upper edges with substantially horizontal webs which together provide a rigidifying chord for said end structure.

3. The combination with the side wall structures of a gondola car, of a metal end wall structure for the car comprising along its upper edge a pair of rigidifying chord members, of substantially inverted channel

shape in cross section, which project in opposite directions from the body of the end structure.

4. The combination with the side wall structures of a gondola car, of a metal end wall structure for the car comprising along its upper edge a pair of rigidifying chord members, of substantially inverted channel shape in cross section, which project in opposite directions from the body of the said end structure, and gusset members secured to the said rigidifying chord and to the said side wall structures.

5. The combination of a side wall structure of a gondola car, of an end wall structure for the car comprising two metal sheets arranged face to face and provided along their upper edges with oppositely disposed flanges providing a rigidifying chord extending across the car from side to side thereof; one of said sheets being formed with a plurality of rigidifying corrugations and provided with angular attaching flanges adapted to be secured to the side walls of the car.

6. The combination of a side wall structure of a gondola car, of an end wall structure for the car comprising a metal sheet formed with rigidifying ribs and with attaching flanges which overlap the outer surfaces of the side walls, a metal sheet arranged against the inner face of said first mentioned sheet and secured thereto on opposite sides of the said rigidifying ribs and having vertical flanges secured to the inner surfaces of the said walls of the car; the upper edges of said sheets being bent in opposite directions to provide a rigidifying chord which extends from side to side of the car.

7. The combination with the side wall structure of a gondola car, of a metal end wall for the car comprising two metal sheets arranged face to face and secured together, formed along their vertical edges with flanges adapted to be secured to the inner and outer surfaces of the side wall structure and having their upper edges bent in opposite directions and said bent portions formed with vertical rigidifying flanges, and angular gusset members having horizontal flanges adapted to be secured to the upper edges of said sheets and with a flange which overlaps the outer surface of said side wall structure and is secured thereto.

8. A sheet metal end structure for a gondola car comprising two metal sheets arranged face to face with their upper edges bent outwardly in opposite directions to constitute a rigidifying top chord for said end structure.

9. A sheet metal end structure for a gondola car comprising two metal sheets arranged face to face with their upper edges bent to form horizontal oppositely extend-

ing webs provided with downwardly projecting flanges to constitute a rigidifying top chord for said end structure.

10. A sheet metal end structure for a gondola car comprising two metal sheets arranged face to face, formed with corrugations disposed so that those of one sheet align with those of the other, and with their upper edges bent outwardly in opposite directions to constitute a rigidifying top chord for said end structure.

11. In combination with the side walls of a gondola car, a sheet metal end structure comprising two metal sheets arranged face to face, with their upper edges bent outwardly in opposite directions to constitute a rigidifying top chord for said end structure, and gusset plates secured to the tops of said side walls and to the outwardly bent upper edges of said sheets.

12. In combination with the under frame of a railway car, a sheet metal end structure comprising two metal sheets arranged face to face with their lower edges bent outwardly in opposite directions and secured to said under frame.

13. In combination with the under frame and side walls of a gondola car, a sheet metal end structure comprising two metal sheets arranged face to face with their upper edges bent outwardly in opposite directions to constitute a top chord, their lower edges bent outwardly in opposite directions and secured to said under frame and their vertical edges bent to provide flanges for engaging said side walls.

14. In combination with the side walls and under frame of a gondola car, a sheet metal end structure comprising two metal sheets arranged face to face with their upper edges bent outwardly in opposite directions to constitute a top chord, their lower edges bent outwardly in opposite directions and secured to said under frame, and their outer edges bent in the same direction to engage the outer and inner sides of said side walls.

15. In combination with the under frame of a gondola car, a metal end structure provided at its upper edge with oppositely extending substantially horizontal webs constituting a top chord for said end structure and at its lower edge with oppositely extending flanges secured to said under frame.

16. In combination with the side walls and under frame of a gondola car, a metal end structure provided at its upper edge with oppositely extending webs constituting a top chord for said end structure, at its lower edge with oppositely extending flanges secured to said under frame, and along its vertical edges with flanges for attachment to the side walls of the car.

17. A sheet metal end structure for a gon-

dola car comprising two metal sheets arranged face to face with their upper edges bent to provide substantially horizontal webs which together constitute a top chord 5 for said end structure.

18. A sheet metal end structure for a gondola car comprising two metal sheets ar-

ranged face to face with their upper edges bent to provide substantially horizontal webs which together constitute a top chord 10 for said end structure and gusset plates for securing said top chord to the side walls of the car.

SAMUEL H. CONWELL.
